Attorney, Agent, or Firm—Edwin L. Spangler, Jr.

[57] **CLAIM**

The ornamental design for a sling for a rifle, as shown and described.

DESCRIPTION

FIG. 1 is a front elevation of a "sling for a rifle" showing my new design;

FIG. 2 is a right side elevation thereof; and,

FIG. 3 is a rear elevation thereof.

The left side elevation is a mirror image of the right side elevation shown.
